UNITED STATES PATENT OFFICE.

ANTHONY ANASTASI, OF BOSTON, MASSACHUSETTS, ASSIGNOR TO ANASTASI LIFE-BOAT COMPANY, OF BOSTON, MASSACHUSETTS, A CORPORATION OF MASSACHUSETTS.

BUOYANT LIFE-BOAT.

1,124,248.

Specification of Letters Patent.

Patented Jan. 12, 1915.

Application filed August 27, 1914. Serial No. 858,856.

To all whom it may concern:

Be it known that I, ANTHONY ANASTASI, a subject of the King of Italy, residing at Boston, in the county of Suffolk and State 5 of Massachusetts, have invented a new and useful Improvement in Buoyant Life-Boats, of which the following is a specification.

This invention relates to buoyant lifeboats which may be folded so as to occupy the 10 least amount of space while positioned on the deck of a ship, and when required for use may be easily and readily opened to provide a lifeboat of high capacity, which affords its passengers convenience, protection 15 against both the weather and seas, and every facility for controlling the boat and bringing it (with its passengers) to a place of safety.

Another object of the invention is to provide 20 an emergency folding buoyant life-boat which may be put into working order easily and quickly, and which affords the passengers of the same every facility for enabling them to manage the same against 25 the various conditions met with on the waters;—permitting the accommodation of a greater number of passengers than the ordinary types of lifeboats, and providing a lifeboat with a sailing equipment for enabling 30 the passengers to sail and guide the boat to a point of safety.

Another object is to provide a folding buoyant lifeboat, equipped with necessary appliances for affording the passengers 35 thereof every facility for safeguarding them and for directing the boat against the conditions of the weather and the seas, as well as providing them with means for sailing to a point of safety;—the boat being dis- 40 signed, when positioned on the deck of a ship, to occupy about the same space as is occupied by the ordinary type of lifeboat, but when unfolded and open for use in the water, has a greater capacity for carrying 45 and accommodating passengers than the ordinary lifeboat,—assuring the passengers safety against the conditions of the weather and the seas, as well as offering them every means for directing and bringing the boat 50 to a point of safety in less time than can be expected from other types of lifeboats.

Still another object is to provide a folding buoyant lifeboat of high passenger carrying capacity, which may be easily lowered 55 into the water and which may be

readily rigged to permit the sailing thereof to a point of safety.

To these as well as other ends, my invention consists in the novel features of construction, combination and arrangement of parts set forth in the following specification and particularly pointed out in the subjoined claims.

Briefly, the preferred form of my invention comprises the hinging together of two buoyant boats or rafts, for enabling them to fold one over the other, when not in use and positioned on the deck of a ship equipped with the same,—the lower boat being provided with two upright posts which may be used as derricks for opening the boats apart, and as masts for carrying sails when the boat is lowered into the water for use in cases of emergency. The boats are provided with sails (preferably of the square rigging type), which may be readily hoisted on the masts, a rudder for steering purposes, and means for coupling and holding the two boats together against folding. The boats are also provided with water-proof awnings or curtains which may be stretched over the same for protecting the passengers both against the weather and seas,—thereby producing a buoyant lifeboat with safe means for enabling the same to carry its passengers to a point of safety and also to protect them against the conditions of the sea while *en route*.

In the drawings illustrating the preferred form of the invention:—Figure 1, is an end view of my type of lifeboat folded and positioned on the deck of a ship and ready for use in case of emergency. Fig. 2, is the same view as Fig. 1, but shows the upper boat hoisted from the folded position, representing the first operation of the handling of the boat just prior to the lowering of the same into the water. Fig. 3, is a plan view of the boat in the open and unfolded position, showing one half of the same covered with the water-proof awning or curtain. Fig. 4, is a view showing the folded buoyant lifeboat in position on the deck of a ship. Fig. 5, is a view showing two positions of the lifeboat, the dotted position indicating the boat swung from the deck on the davits and ready for lowering, while the lower position shows the boat lowered into the water and open in working position ready for the hoisting of the sails. Fig. 6, is a

perspective view of the lifeboat lowered in the water, with but one of the sails hoisted, showing the boat ready for use. Fig. 7, is a side view of the boat showing the same under sail, with both sails hoisted and with the rudder for steering the boat attached thereto. Fig. 8, is a sectional view taken through the mid-section of the boats when unfolded and coupled together for use, showing the air-chambers in the bottoms of the same for providing the boats with the buoyant feature.

In that embodiment of the invention shown in the drawings, the numeral 1 is the hull of a ship, having the deck 2, which is provided with the davits 3, which davits are in turn provided with the tackle consisting of the upper pulley 4 and the lower pulley 5 equipped with the rope or cable 6 which may be fastened to the cleat 7 which is fixed to the davit 3. The lower pulley 5 is provided with the hook 8 for engaging with the lifeboat supports 9 which are fastened to the ends 10 of the lower boat 11. The lower boat 11 is preferably provided with the common type of roller casters 12 which permit easy handling of the lifeboat on the deck 2. The upper boat 13 is hinged to the lower boat 11 by means of the hinges 14, which connect the inner sides 15 and 16 of the boats 11 and 13, respectively.

The lower boat 11 is provided with the masts 17, which are rigidly secured thereto, and which are provided with the tackles 18 and 19, the tackle 18 being connected with the side 20 of the boat 13 for handling the same, while the tackle 19 is provided for the raising of the sails 21. The mast 17 is braced by the brace 22, which is fixed to the lower boat 11.

The boats 11 and 13 are coupled together by means of the coupling-ropes or cable 23 which are positioned at both ends of the boat and which have the ends 24 permanently fastened to the boat 13. The coupling-ropes pass through the eye-bolts 25 and preferably come through the holes 26 in the boat 11 and are coupled with the cleats 27 provided for the purpose.

The boats 11 and 13 are provided with the air-chambers 28 for producing the buoyant feature in the same, which enables them to carry appreciable loads and to resist sinking. The boats 11 and 13 are also provided with the water-proof awnings or curtains 29 which are preferably made of canvas and may be stretched over the tops of the boats by means of the awning-ropes 30, which ropes may be fastened to the cleats 31 provided in the boats 11 and 13 for the purpose.

The boats may be preferably provided with the benches or bunks 32 which provide the storing-room 33 between the bunks 32 and the flooring 34. The boats may also

be provided with the rudder 35 which may be attached to either end of the open boat, as shown in Figs. 3 and 7.

Having thus described the parts of my invention in detail, the manner in which the same is used is as follows:—The normal position of the lifeboat is the folded position, as shown in Fig. 1, where the same rests on the deck 2 on the casters 12, with the lifeboat supports 9 coupled to the lowering tackle provided on the davits 3—the folded boat being supported in any suitable manner against moving on the deck from the position shown in Fig. 1. As soon as necessity requires the use of the lifeboat and the same is to be lowered into the water, the first operation of the crew should be the raising of the upper boat 13, by means of the tackle 18 provided for the purpose, raising the same to the preferred position, shown in Fig. 2. After this is done, the supports that are used for keeping the boat in position on the ship may be removed and the rope 6 may be released from the cleat 7 for raising the boat from the deck 2. The davits 3 are then swung outward from the ship 1 (as shown in Fig. 5) and the boat is then lowered into the water by the slackening of the rope 6, as shown. One or two members of the crew may get into the boat while the same is being lowered, and when the boat nears the water may open the upper boat 11 by means of the tackle 18 to the lower position, shown in Fig. 5. As soon as the boat 13 is thus opened and lowered into the water by pulling in the coupling-ropes or cables 23 until the sides 15 and 16 are butted together, as shown in Fig. 8, and securing the ropes 23 to the cleats 27, the boats 11 and 13 are coupled together and form one open boat, as shown in Fig. 6. After the lifeboat is lowered, the same may be filled with passengers and the lifeboat-supports 9 may be released from the hooks 8 and thereby free the lifeboat from the ship 1. The rudder 35 may be set in position, (as shown in Fig. 7) and the sails 21 may be hoisted on the tackle 19 provided therefor, and by the crew or passengers manning the sails and the rudder, the boat may be directed to a point of safety with very little trouble.

If a covering is required for shielding the passengers against the weather conditions or the conditions of the sea, the curtain or awning 29 may be drawn over the boat by means of the ropes 30, which may be fastened to the cleats 27 for keeping the awnings in position. The boats may be equipped with the necessary incidentals that may be required for the comfort and use of the passengers, to afford them every convenience while being carried to safety.

After the lifeboat has been used and it is required to be again positioned on the deck

of a ship, the sails 21 may be lowered, folded or rolled in a roller, (as shown in Figs. 3 and 6) and positioned within the boat. The awnings may be rolled back as shown 5 in the boat 11 in Figs. 3 and 8 and in the boat 13 in Fig. 6. The coupling-ropes 23 may be disengaged from the cleats 27 which will free the boat 13 so that it may be hoisted by the tackle 18 and folded over the boat 11. The lifeboat supports 9 may be then engaged with the hooks 8 of the pulleys 5, and the boat may be hoisted on the davits 3 with the cables or ropes 6, for positioning the boat on the deck 2 of the ship 1 (as 10 shown in Fig. 1) again ready for service.

It may be observed that this type of folding-buoyant-lifeboat offers every advantage for saving passengers of ships meeting with accidents while on the waters, and permits 15 the accommodation and handling of many more passengers than could possibly be taken care of by the ordinary types of lifeboats.

This type of boat practically takes the place of a large raft, but is specially 20 equipped to provide comfort and safety for the passengers that it carries,—the same being built of any desired size, depending upon 25 the number of passengers to be cared for.

While I have shown the boat provided 30 with the air-chamber for producing the buoyant feature, I do not wish to be limited against eliminating that feature and using the plain boats in the same manner, as has been heretofore described.

It may be understood that while the boat 35 is provided with sailing means, the same need not be employed where it is not required, and when required the boat affords the use of one sail or two sails, which may be 40 easily hoisted in position and manned by the passengers. Also, while I have shown the rudder attached to one end of the lifeboat, the same may be attached to the opposite 45 end to equal advantage, when desired.

It may be further understood that while 50 I have not shown any accessories or other incidentals usually found equipped in life-boats, the same may be easily provided in this type of lifeboat, there being ample space to store same within the boats.

While the preferred embodiments of my invention have been described in detail, it will be understood that I do not wish to be limited to the particular construction set 55 forth, since various changes in the form, material, proportion, arrangement of parts, and in the details of construction may be resorted to without departing from the spirit and scope of the invention, or destroying 60 any of the advantages contained in the same, heretofore described and defined in the subjoined claims.

What I claim is:—

1. The combination of two boats hinged 65 together and adapted to be folded one over

the other; means for folding and unfolding the same; means for coupling the same together when unfolded; means for sailing the unfolded and coupled boats; means for steering the coupled boats and means for covering the tops of the boats, substantially as 70 shown.

2. The combination of two buoyant boats hinged together and adapted to be normally folded one over the other; means for folding and unfolding the same; means for coupling the same together when in the unfolded and open position; means for sailing the boat; means for steering the boat; means for covering the boat; and supporting means, 75 80 substantially as shown.

3. The combination of two independent boats provided with buoyant chambers and adapted to be folded one over the other; upright posts provided at the ends of one of 85 said boats and rigidly secured thereto and provided with tackles for the handling of the other of said boats and with extra tackles; coupling means adapted to rigidly secure the boats when unfolded and open for use; sailing means adapted to be hoisted on said extra tackle of said upright posts; steering means adapted to be secured to said open boat; water-proof awnings provided in each of said boats for covering the same 90 95 against the conditions of the sea and weather, for protecting the interiors of said boats, substantially as shown.

4. The combination of two rectangular shaped buoyant boats, foldably hinged together and adapted to be normally folded one over the other; masts rigidly secured to the folding side of one of said boats at the ends of the same, and provided with a plurality of tackle outfits, one of said tackles 100 105 engaging with the other of said boats for handling the same; coupling-cables or ropes provided at the ends of said boats and adapted to secure the boats together when open, against folding; sailing means adapted to 110 engage with the tackle provided on said masts for hoisting the same into working position; a rudder adapted to be secured to an end of said open boat for steering the same; awnings provided at the outer sides 115 of said boats and adapted to cover the same; and supporting means adapted to engage with the tackle provided on the davits of a ship for raising or lowering the lifeboat, substantially as shown.

5. The combination of two rectangular shaped buoyant boats, foldably hinged together and adapted to be normally folded one over the other; masts rigidly secured to the folding side of one of said boats at the 120 125 ends of the same, and provided with a plurality of tackle outfits, one of said tackles engaging with the other of said boats for handling the same; coupling-cables or ropes provided at the ends of said boats and 130

adapted to secure the boats together, when open, against folding; sailing means adapted to engage with the tackle provided on said masts for hoisting the same into working position; a rudder adapted to be secured to an end of said open boat for steering the same; rolling awnings provided at the sides of said boats and adapted to be unrolled for covering the same; and supporting means adapted to engage with the tackle provided on the davits of the ship for raising or lowering the lifeboat, substantially as shown.

6. The combination of a plurality of boats hinged together and adapted to be normally folded one over the other; means for unfolding the same for forming a unit of said boats; means for coupling and uniting the boats together when unfolded; means for sailing the unit boat; means for steering the unit boat; and means for covering the boat, substantially as shown. 15 20
